UNITED STATES PATENT OFFICE.

HARRY E. RHOADS, OF TOLEDO, OHIO, ASSIGNOR TO THE WILLYS-OVERLAND COMPANY, OF TOLEDO, OHIO, A CORPORATION OF OHIO.

FUEL HEATER FOR INTERNAL-COMBUSTION ENGINES.

Application filed February 10, 1919. Serial No. 276,124.

This invention relates to an improved fuel heater for internal combustion engines, comprising a manifold construction having the parts so arranged that the fuel mixture is heated by contact with a portion of the exhaust manifold carrying the combustion products.

One object of the invention is to provide a device of this character, wherein the parts are so arranged as to give a more uniform quality to the fuel mixture.

Another object of the invention is to provide an improved method of controlling and vaporizing the mixture for an internal combustion engine before admitting it to the cylinders thereof.

A further object of the invention is to provide a device of this character wherein the heavier portions of the fuel mixture are brought into more intimate contact with the heating surface of the exhaust manifold than the lighter and more volatile portions thereof.

A further object of the invention is to provide a device of this character which is of simple construction and efficient in operation.

Further objects of this invention relate to economies of manufacture and details of construction, as will hereinafter appear from the detailed description to follow.

The objects of the invention are accomplished in one instance by the devices and means described in the following specification, but it is evident that the same may be varied widely without departing from the scope of the invention as pointed out in the appended claims.

A structure constituting one embodiment of the invention, which may be the preferred, is illustrated in the accompanying drawing forming a part hereof, in which:—

Figure I is a side elevation view of an internal combustion engine of the type ordinarily employed for use upon automobiles, illustrating the fuel supply passage and its relation to the exhaust manifold.

Figure II is a top plan view of the exhaust manifold, illustrating the relative position with respect thereto of the fuel supply passage.

Figure III is a side elevational view of the exhaust manifold, with a portion of the

fuel supply passage shown in section for the purpose of better illustrating its relation to the exhaust manifold.

Figure IV is a sectional view taken upon the line IV—IV of Figure III, and illustrating the form and relative location of the passages through which the fuel is conducted to the intake opening in the cylinder casing.

It has been found to be particularly desirable in the use of kerosene or low grade gasoline as a fuel, to employ some means for heating the gaseous fuel after it leaves the carburetor, so as to render it more efficient in developing power. In order to accomplish this result in such a manner as to produce a substantially uniform mixture, and to insure that the heavier portions of the fuel are subjected to a greater extent to the heating action of the exhaust manifold than the lighter and more volatile portions thereof the present arrangement of conducting passages is employed.

In the embodiment of the invention illustrated herewith, 10 indicates any internal combustion engine which is provided with an exhaust manifold 11 having a plurality of branches 12, which in the present instance

are four in number, adapted for engagement with the exhaust openings in the cylinder head casing of the engine. The various branches 12 of the exhaust manifold converge into a common trunk 13, which is provided with a shoulder 14 adapted to be bolted or otherwise suitably secured to one end of the muffler (not shown).

The exhaust manifold is secured to the engine casing in any suitable manner, it being illustrated in the present instance as being provided with a plurality of projecting stems 15, preferably arranged in pairs, each pair being adapted for engagement by the opposite ends of a head plate 16, which is in turn

adapted to be secured to the engine casing by means of a bolt 17 projecting from the engine casing and passing through the central portion of the head plate, and secured in place by a nut 18 which is adapted to bear

against the outer portion of the corresponding head plate.

The main fuel pipe 20 connects the carburetor 21 with a source of fuel supply (not shown), and is adapted to be supported by a bearing 22. That portion of the fuel

supply pipe lying between the carburetor and the engine casing and forming a passage for the fuel mixture is preferably cast integral with the exhaust manifold and is 5 provided at one extremity with a coupling portion 23, adapted to be secured to the carburetor by means of bolts or other suitable fastening means 24. A spacing collar 25 for carrying a throttle valve may be in- 10 terposed between the coupling portion 23 and the corresponding end of the carburetor casing to which the frame is adapted to be connected. That portion of the fuel supply passage extending between the carburetor 15 and the engine casing and designated by the numeral 19 is provided at the opposite extremity from the collar 23 with a shoulder 27 adapted to fit against the intake opening of the engine casing in such a manner as to 20 place the fuel supply passage 19 in free communication thereof.

The portion 19 of the fuel supply pipe is shown surrounding one portion of the exhaust manifold 11 between two branch 25 portions 12 and the common trunk 13, being positioned at substantially right angles to the longitudinal axis of the same, and the portion 19 of the fuel supply pipe takes a sharp bend at the point where it surrounds 30 the branch 12 of the exhaust manifold, so that the portions of the fuel supply passage extending in opposite direction from the portion 12 of the exhaust manifold make an angle of considerably less than 180° with 35 respect to each other. That portion of the fuel supply passage which is adjacent the carburetor is indicated by the reference character 28 upon the drawing, while that portion of the fuel supply pipe nearest the 40 engine casing is designated by 29. A baffle 30 is provided within the fuel supply passage at a point near where the passage is enlarged for the purpose of embracing the branch 12 of the exhaust manifold. A pair 45 of branch passages 31 and 32 are formed in the fuel supply passage due to the construction by which it embraces the branch 12 of the exhaust manifold. It will be noted upon reference to Figure IV that the passage 31 is of considerably greater length 50 than the passage 32, and is also narrowed throughout a portion of its length to a less width than the passage 32.

As the incoming gases pass through the 55 portion 28 of the fuel supply passage, they strike against the baffle 30 and tend to become deflected in the direction of the full line arrows shown in Figure IV so as to pass through the branch passage 31 of the supply passage. From Fig. IV it will be 60 seen that the passage 32 makes a more abrupt turn than the passage 31 on branching from the main passage 28, and that centrifugal force acting upon the fuel particles passing 65 that portion of the baffle 30 nearest the

tubular passage 28, will tend to throw the heavier particles of fuel outwardly and into the passage 31 having the greater vaporizing power, while the lighter and more volatile portions of the gaseous fuel are influenced 70 to a greater extent by the suction of the intake passage than the heavier portions thereof, and are consequently drawn within the branch passage 32, as shown by the dotted line arrow, immediately after passing 75 the baffle 30. It will be observed that the branch passage 31 is in contact with the heated surface of the branch 12 of the exhaust manifold during a considerably greater portion of its length than is the passage 80 32. It will also be seen that the passage 31 is narrowed throughout a portion of its length so that the gases carried therethrough come in closer contact with the heated portion 12 of the exhaust manifold 85 than those carried by the passage 32. From this construction it results that the heavier portions of the gaseous fuel, which are deflected so as to pass through the branch passage 31 will be subjected to the influence of 90 the heat emanating from the exhaust manifold to a greater degree, and throughout a greater portion of their travel than will those lighter more volatile gases which are drawn through the passage 32. In this way 95 a substantially uniform combustion product is attained, and the lighter and heavier portions of the gaseous fuel are selectively treated in such a manner as to tend to vaporize particularly those portions which are 100 heavier and less volatile. By this construction, means is provided for selectively exposing to a greater degree of vaporizing action the heavier portion of the gaseous fuel, while at the same time permitting the lighter 105 portions thereof to pass through the fuel supply passage without being subjected to the same intensity or duration of heat as the heavier portions, thus producing a more uniform fuel as it is passed into the intake 110 passage of the engine casing.

This arrangement of branched passages contacting with a heated portion of the exhaust manifold and constructed as described above, not only result in securing a more uniform fuel by reason of the subjecting of the heavier portions of the fuel to the vaporizing action of the heated surface to a greater extent than the more volatile portion thereof, but also improve the quality of all 115 of the fuel by exposing it to a greater or less degree to the vaporizing action of the heated surface, thus breaking up the usual low grade fuel so as to render it more efficient as a motive force.

While I have shown and described in considerable detail a specific embodiment of my invention, it is to be understood that this showing and description is illustrative only, and for the purpose of rendering my inven- 120 125 130

tion more clear, and that I do not regard the invention as limited to the details of construction illustrated or described, nor any of them, except in so far as I have included such limitations within the terms of the following claims, in which it is my intention to claim all novelty inherent in my invention broadly as well as specifically.

What I claim as new and desire to secure 10 by Letters Patent is: —

1. In a fuel vaporizing device, an exhaust pipe, a fuel inlet conduit having two branches each partially surrounding said exhaust pipe, one being arranged to traverse 15 a greater portion of the exhaust pipe than the other, whereby to provide passages of different vaporizing power, said conduit being so shaped as to cause the heavier particles of the fuel by centrifugal action to 20 traverse the passage having the greater vaporizing power when suction is produced in said passages.

2. In a fuel heating structure, an exhaust manifold, a fuel supply passage contacting with the exterior surface of a portion of the exhaust manifold and having a pair of branch passages, one of said passages being in contact with the exterior surface of the exhaust manifold throughout a greater portion of its length than the other and being more nearly aligned with the path of the entering fuel.

3. In a fuel heating structure, an exhaust manifold, a fuel supply passage contacting with a portion of the exterior surface of the exhaust manifold and having a pair of branch passages of unequal width for admission of the fuel, and means for deflecting the heavier portions of the fuel through the narrower passage while permitting the lighter portions of the fuel to be drawn through the wider passage.

4. In a fuel heating structure, an exhaust manifold, a fuel supply passage contacting with a portion of the exterior surface of the exhaust manifold and having a pair of branch passages of unequal lengths for admission of the fuel, and means for deflecting the heavier portions of the fuel through the longer passage while permitting the lighter portions to be drawn through the shorter passage.

5. In a fuel vaporizing device, an exhaust pipe, a fuel supply conduit including a pair of branch passages of unequal heating areas, each partly surrounding and contacting with the exterior surface of the exhaust pipe, and a baffle within said conduit for deflecting the heavier portions of the fuel into one of said passages and permitting the lighter

portions to be drawn into the other passage when suction is produced in said passages.

6. In a fuel vaporizing device, an exhaust pipe, a fuel supply pipe including divided passages of unequal length each surrounding a portion of said exhaust pipe, and a baffle in the supply pipe for directing the fuel whereby the inertia of the heavier particles of the fuel causes them to traverse the passage of the greater length when suction is produced in said passages.

7. In a suction controlled vaporizing device, a heated conduit, a fuel supply pipe provided with branch passages having portions thereof contacting with unequal portions of the exterior wall of said conduit, and a baffle in the supply pipe for directing the heavier elements of the mixture into one of the passages and permitting the lighter elements to be drawn into the other passage when suction is produced in said passages.

8. In a suction controlled vaporizing device, a heated member, a fuel supply conduit provided with a plurality of branch 85 passages, each of which extends around a portion of said heated member and one of which has a restricted outlet, and means for directing the heavier particles of fuel into the passage having the restricted outlet and 90 permitting the lighter particles to be drawn through the other passage when suction is produced therein.

9. In a suction controlled fuel vaporizing device, a heated member, a fuel conduit having divided passages each adapted to partially surround different portions of the heated member, and a baffle for deflecting the heavier portions of the fuel into one of the passages and permitting the lighter portions to be drawn into the other passage when suction is produced therein.

10. In an intake manifold, an exhaust passage, a fuel supply passage surrounding a portion of the exhaust passage to form a pair of branched passages of unequal length, and a baffle cooperating with said passages to direct the heavier portions of the fuel through the longer branch, thereby exposing them to a greater extent to the vaporizing effect of the exhaust heat.

11. In a device of the character described, an exhaust manifold, and means providing a fuel passage leading to and around said manifold, said means including a deflector for directing particles of unvaporized fuel against the outer surface of said passage.

In testimony whereof, I affix my signature.

HARRY E. RHOADS.
